OBADIAH C. MAXWELL, THOMAS L. NEAL, AND CHARLES L. LONG, OF DAYTON, OHIO.

Design No. 3,887, dated March 8, 1870.

DESIGN FOR A TRADE-MARK.

The Schedule referred to in these Letters Patent and making part of the same.

To all whom it may concern:

Be it known that we, OBADIAH C. MAXWELL, THOMAS L. NEAL, and CHARLES L. LONG, partners, as Maxwell, Long, & Co., of the city of Dayton, in the county of Montgomery, and State of Ohio, have originated and designed a new Design for a Trade-Mark, of which the following is a full, clear, and exact description, reference being had to the accompanying specimen, marked Exhibit A, and making part of this specification.

Description.

A rhombus or diamond-shaped figure with the word "soaps" within the same, and the words "trade-mark" on the bar of the letter A in said word "soaps," the lines forming the rhombus not to be confined to any particular length, and the letters of the words "soaps" and "trade-mark" not to be confined to any particular size or style, that petitioners may use the same in different-sized packages, boxes, labels, &c.

Claim.

What we claim as our invention, and desire to secure by Letters Patent, is—

The design for a trade-mark herein set forth.

OBADIAH C. MAXWELL.
THOMAS L. NEAL.
CHARLES L. LONG.
